UNITED STATES PATENT OFFICE.

EDWARD S. STIMPSON, OF HOPEDALE, MASSACHUSETTS, ASSIGNOR, BY MESNE ASSIGNMENTS, TO DRAPER CORPORATION, OF PORTLAND, MAINE, A CORPORATION OF MAINE.

LOOM-SHUTTLE.

1,212,278.

Specification of Letters Patent. Patented Jan. 16, 1917.

Application filed August 6, 1914. Serial No. 855,455.

To all whom it may concern:

Be it known that I, EDWARD S. STIMPSON, of Hopedale, in the county of Worcester and State of Massachusetts, have invented certain new and useful Improvements in Loom-Shuttles, of which the following is a specification.

The present invention relates to automatically threading shuttles of the character that are used in weft replenishing looms wherein the replenishment is effected by ejecting the spent weft carrier from the shuttle and substituting in its place another filled weft carrier.

15 The object of the present improvements is to render difficult the unthreading of the shuttle after it has once been threaded.

The improvements are illustrated in the accompanying drawings, in which—

20 Figure 1 is a plan view of the eye end of the shuttle. Fig. 2 is a transverse section in the plane indicated by the line 2—2 in Fig. 1. Fig. 3 is a longitudinal section with parts of the shuttle body broken away showing the threader in side elevation. Fig. 4 is a perspective view of the thread deflector. Fig. 5 is a horizontal section in the plane indicated by the line 5—5 in Fig. 3. Fig. 6 is a transverse section in the same plane as 25 Fig. 2, showing the inner guard in a reverse position. Fig. 7 is a transverse section in the plane indicated by the line 7—7 in Fig. 1.

For the purpose of identification, in the 30 present specification, the "front" side of the shuttle is that where the eye is located; the opposite side of the shuttle is the "rear" side; the "inner" end of the thread passage is that which is adjoining the shuttle chamber which contains the weft carrier; and the "outer" end of the thread passage is that which communicates with the delivery passage L near the tip of the shuttle at the eye end. Accordingly, "outwardly" is toward 35 the tip of the shuttle at the eye end; "inwardly" is toward the shuttle chamber; "forwardly" is toward the eye side of the shuttle; and "rearwardly" is toward the rear side of the shuttle.

40 The present improvements are shown as applied to an automatically threading shuttle which is substantially similar to that shown in United States Letters Patent No. 933,497, September 7, 1909. The shuttle A

has a threading chamber B at its eye end in 55 which is located a sheet metal threader. As in said patent this sheet metal threader comprises separated vertical side walls C, D, with a threading passage E, between them; a beak F, at the outer end of the thread passage which is located at the front or eye side of said passage and extends outwardly beyond and overhangs the outer end of the threading passage and directs the thread to the slotted eye G, of the shuttle; a guard H, 60 at the outer end of the threading passage which extends forwardly from the rear of the threading passage and overhangs the beak F; and a guard I, at the inner end of the threading passage which retains the 65 thread in the threading passage between the two side walls of the threader. The wall C, is at the eye or front side of the shuttle and the wall D, is at the opposite or rear side. The threader is held in place by means of a 70 transverse bolt J, which extends through apertures in the shuttle body and in the walls of the threader, this bolt screwing into a nut K, countersunk in the rear side of the shuttle body, as shown in Fig. 2. The beak 75 F, has a downwardly and inwardly inclined edge a, which directs the thread from the delivery passage L, to the eye G, and at the extreme lower end of this inclined edge is a heel b, which constitutes a portion of the 80 outer wall of the eye. In all of these respects the construction is substantially as shown in said Patent No. 933,497.

The present improvements are three in 85 number and relate to the loop retainer R, the shoulder T, and the thread deflector S. These will be separately described.

As shown in the aforesaid Patent No. 933,497, the inner edge of the outer guard (corresponding to the herein illustrated 90 guard H) is forwardly and outwardly inclined with the result that if a loop of the thread is thrown upwardly, as sometimes happens, due probably to the sudden stoppage of the shuttle, such loop may be guided 95 outwardly thereby occasionally unthreading the shuttle and sometimes causing thread breakage. In accordance with the present invention the inner edge R, of the guard H, extends abruptly to the axis of the thread- 100 ing passage E, and across and over said passage, so that it catches and retains the upwardly extending loop of thread. This edge 105

R, extends forward beyond the front wall of the threading passage. Thus this inner edge constitutes a loop retainer to retain the thread in the threading passage E. The 5 loop retainer is above the eye, and no part of it is located beyond said eye outwardly.

The shoulder T, (which in the illustrated embodiment of the invention is constituted by a portion of the wooden body of the 10 shuttle) has three faces or walls c, d, e. The upper face c, is horizontal and it is located below the point f, of the beak and above the heel b of the beak, as shown in Fig. 7. The wall d, is substantially vertical and extends transversely of the threading passage 15 and at the outer end thereof. Its forward edge extends vertically substantially in the vertical transverse plane which intersects the lowest point of the heel b, as shown in Fig. 20 3, with the result that the said surface d is outside of the eye. The third wall e, is vertical and extends lengthwise of the shuttle and forward of the middle longitudinal axis of the threading passage, and forward 25 of the front wall of said passage, as shown in Fig. 5. This longitudinal wall e, is at the rear of the rear face of the beak F, so that a narrow slit g is left for the entrance of the thread between said longitudinal surface 30 e, and the beak. The two walls of this slit are thus constituted by said longitudinal wall e, and by the beak F. The thread is readily guided into this slit but the narrowness thereof makes it difficult for the 35 thread to escape after it has once entered the eye.

The thread deflector S, is constituted by a block of hard metal which fits between the side walls C and D of the threader. 40 This thread deflector is held in place by the bolt J, which extends through a hole h, in the deflector and by a forwardly projecting nose i, which enters an aperture j, in the front wall C, of the threader. By 45 reason of this nose i, fitting in the aperture j, it becomes impossible for an entering thread to get caught between the upper edge of the deflector and the wall C. The upwardly projecting front side k, of the deflector maintains the thread in the thread 50 passage E, back of the longitudinal surface e, of the shoulder T, and hence back of the slit g. Accordingly, in the case of a forward jump of the thread the deflector causes 55 it to impinge against the transverse wall d, of the shoulder instead of jumping into the slit. The lower portion l, of the deflector constitutes the floor of the threading passage upon which the thread runs. The 60 outer end of the deflector terminates inside of the eye so that the thread in passing from the threading passage to the eye reeves around the outer end of the deflector. The deflector being of hard metal does not wear 65 readily under the action of the thread. The

deflector fills the space between the walls C, and D, thus maintaining said walls properly spaced.

The front side k, of the deflector constitutes the front wall of the threading passage E, and, hence, said passage E, and the slit g, are not in line with each other, said slit being forward of said passage.

The inner guard I, extends to the right (Fig. 6) or the left (Fig. 2), depending 75 upon the wind of the yarn on the weft-carriers with which the shuttle is used.

I claim—

1. An automatically threading shuttle having, in combination, a sheet metal 80 threader with separated side walls, one of said walls having a hole, and a thread deflector fitting between said walls to hold them apart and having a nose entering said hole.

2. An automatically threading shuttle having, in combination, a threading passage; a beak at the eye or front side of the threading passage extending outwardly beyond and overhanging the slotted eye of the shuttle; a thread guard at the inner end of the 90 threading passage; and an outer guard at the outer portion of said threading passage extending from the rear of the threading passage and overhanging the point of 95 the beak, said guard having a loop retainer at its inner end extending abruptly across and over the threading passage and above and in line with the eye, and extending forwardly beyond the front wall 100 of the threading passage.

3. An automatically threading shuttle having, in combination, a threading passage; a beak at the eye or front side of the threading passage extending outwardly 105 beyond and overhanging the slotted eye of the shuttle; a thread guard at the inner end of the threading passage; and an outer guard at the outer portion of said threading passage extending 110 from the rear of the threading passage and overhanging the point of the beak, said guard having a loop retainer at its inner end extending abruptly across and over the 115 threading passage and extending forwardly beyond the front wall of the threading passage.

4. An automatically threading shuttle having, in combination, a threading passage; a slotted eye; a thread guard at the inner 120 end of the threading passage; and an outer guard at the outer portion of said threading passage extending from the rear of the threading passage and overhanging said passage, said guard having a loop retainer 125 at its inner end extending abruptly across and over the threading passage and extending forwardly beyond the front wall of the threading passage.

5. An automatically threading shuttle 130

having, in combination, a threading passage; a slotted eye; an upwardly and rearwardly extending beak overhanging said passage; and a shoulder at the outer end of said passage having a longitudinal wall, a transverse wall, and an upper face, said longitudinal wall extending alongside the lower portion of the beak forward of the front wall of the threading passage and separated from 10 said beak so as to constitute a narrow slit through which the thread passes on its way from the threading passage to the eye during the threading operation, said transverse wall being at the outer end of the threading passage 15 and at the heel of the beak, and said upper face being located in a plane below the point of the beak and above the heel of the beak.

6. An automatically threading shuttle having, in combination, a threading passage; a 20 beak at the eye or front side of the threading passage overhanging the slotted eye of the shuttle; an outer guard extending from the rear of the threading passage and overhanging the point of the beak, and a narrow 25 thread slit back of the beak and forward of the front wall of the threading passage, and in communication at its inner end with said passage.

In witness whereof, I have hereunto 30 signed my name in the presence of two subscribing witnesses.

EDWARD S. STIMPSON.
